US00D651084S

(12) **United States Design Patent**
Eaton et al.

(10) **Patent No.:** US D651,084 S
(45) **Date of Patent:** ** Dec. 27, 2011

(54) **RAZOR PACKAGE**

(75) Inventors: **Meaghan Grace Eaton**, New York, NY (US); **Carl Andrew Gerhards**, New York, NY (US); **Andrew Anthony Markle**, New York, NY (US)

(73) Assignee: **The Gillette Company**, Boston, MA (US)

(**) Term: **14 Years**

(21) Appl. No.: **29/401,150**

(22) Filed: **Sep. 8, 2011**

D478,008 S 8/2003 Rade et al.
D483,480 S 12/2003 Braverman et al.
D496,267 S 9/2004 Tommassetti

(57) **CLAIM**

The ornamental design for a razor package, as shown and described.

DESCRIPTION

(62) Division of application No. 29/387,719, filed on Mar. 17, 2011, now Pat. No. Des. 647,795.

(51) **LOC (9) Cl.** 09-07

(52) **U.S. Cl.** D9/435

(58) **Field of Classification Search** D9/682, D9/600, 457, 454, 441, 434, 432, 430, 415, D9/414, 418, 704, 552, 551, 669, 750; D11/95; D5/56; D20/40, 36, 28, 27, 26, 22, 11; D14/492, D14/489, 486; 715/976, 840, 764, 715; 229/923, 229/922, 87.19, 116.5, 116.1, 100; 220/694, 220/376

See application file for complete search history.

FIG. 1 is a perspective view of the package of the present invention;

FIG. 2 is a front elevational view of the package of FIG. 1; FIG. 3 is a rear elevational view of the package of FIG. 1; FIG. 4 is a left side elevational view of the package of FIG. 1; FIG. 5 is a right side elevational view of the package of FIG. 1;

FIG. 6 is a top plan view of the package of FIG. 1; FIG. 7 is a bottom plan view of the package of FIG. 1;

FIG. 8 is a perspective view of another embodiment of a package of the present invention;

FIG. 9 is a front elevational view of the package of FIG. 8; FIG. 10 is a rear elevational view of the package of FIG. 8; FIG. 11 is a left side elevational view of the package of FIG. 8;

FIG. 12 is a right side elevational view of the package of FIG. 8;

FIG. 13 is a top plan view of the package of FIG. 8; and, FIG. 14 is a bottom plan view of the package of FIG. 8. The broken lines are shown to depict environmental subject matter only and form no part of the claimed design.
